UNITED STATES PATENT OFFICE

CHARLES S. BUSHNELL, OF ROCHESTER, NEW YORK, ASSIGNOR TO GENERAL RAILWAY SIGNAL COMPANY, OF GATES, NEW YORK, A CORPORATION OF NEW YORK

INSTRUMENT CASING FOR TRAIN-CONTROL SYSTEMS

Application filed May 31, 1923. Serial No. 642,652.

This invention relates to housing and supporting means, and particularly to means for supporting sensitive electro-responsive devices for train control systems on railway vehicles.

The present application is a continuation in part, of applicant's co-pending application Ser. No. 531,903 filed January 26, 1922, now Patent No. 1,717,330, granted June 11, 1929, for all the subject matter common to the two applications.

In providing means for automatically controlling trains in accordance with traffic conditions ahead, it is found expedient to communicate control influence from the trackway to the moving vehicle, so that the train may be automatically brought under control when it approaches another train ahead or a track section in danger for some other reason. It is found desirable to transmit such control influences through an intervening air gap, and to accomplish this very sensitive electro-responsive devices are necessarily employed. In order to prevent such devices from opening or closing a circuit by reason of jars and vibration, it is found expedient to mount such devices on a spring mounting suitably damped so as to cause the oscillation of such mounting to be subdued. Also, such supporting structure should provide protection for these devices from moisture, freezing, detrimental gases, and the like.

With the above and other considerations in mind, it is proposed in accordance with the present invention to provide an inner casing spring-mounted within an outer casing for both horizontal and vertical oscillatory movement, and to provide friction means acting as a brake to absorb the energy transferred into the resilient supporting system by such jars and vibration. Another object of the invention consists in the provision of one casing within another so that sudden fluctuations in temperature in the inner casing do not take place, which might cause condensation of the moisture in the air within the casing and also to protect the electro-responsive mechanism generally, the outer casing serving as a housing for the

resilient supporting and the friction energy absorbing means.

Other objects, purposes, and characteristic features of the invention will appear as the description progresses.

55

In the detailed description of the invention, reference is made to the accompanying drawings, in which:

Figure 1 illustrates a plan view of a mounting embodying the present invention, 60 the covers of both the inner and outer casings being partly broken away to show the internal construction and mechanism;

Fig. 2 is a vertical section taken on the line 2—2, Fig. 1, as viewed in the direction of 65 the arrows;

Fig. 3 is a similar view taken on the line 3—3, Fig. 1; and

Fig. 4 is a vertical section taken on the line 4—4, especially illustrating the manner 70 in which the covers are secured to the casings.

Referring to the drawings, the inner casing I is preferably constructed of cast iron and is provided with inwardly extending 75 lugs 1 defining a horizontal plane substantially midway between the top and bottom thereof. On these lugs is supported an instrument supporting base plate 2, having bosses projecting therefrom and secured in 80 place by cap screws 3 so as to rest on these bosses. This base plate is slightly smaller than the inside of the casing, so that a certain amount of clearance is present to 85 permit the various control wires to be brought from the compartment below the base plate to the top of this base plate where they may be secured to sensitive electro-responsive devices of various kinds, such as the time element device 4, the relays contained in the casing 5, and other devices shown. This casing I is provided with an outwardly extending lug 6 at each corner thereof. To the top and bottom sides of 90 these lugs are fastened flanged spring centering devices 8 and 9, respectively, which are secured by a rivet 10.

The outer casing O has each of its bottom corners provided with a raised seat 12 which has a round upstanding boss 12¹ in- 100

tegral therewith, around which is adapted to seat a compression coil spring 13 containing in its upper end thereof the corresponding spring centering device 9. This construction, it will be noted, affords a resilient support for the inner casing I as far as up and down motion is concerned. In order to limit the relative upward movement of the inner casing, another compression coil spring 15 is seated on top of the spring centering device 8 at each corner of the casing. On each side of the raised seat 12 near the top of the casing O are provided inwardly extending lugs 16 to which is fastened a curved bridge 18 (see Figs. 1 and 3) by cap screws 17. This curved bridge 18 is provided with a threaded hole near its middle containing an adjustable stud 19, which has its reduced portion extending into a flanged collar 20. This flanged collar 20 seats on top of the compression spring 15, thereby effecting a seat to prevent the inner casing from moving upward beyond a predetermined limit.

In assembling this structure, the inner casing I is set into the outer casing O upon the lower spring 13. A suitable weight may then be placed upon the inner casing, thereby forcing it down sufficiently to allow the upper spring 15 and its retaining means including the flanged collar 20 and bridge 18 to be put in place. If additional initial tension of the springs 13 and 15 is desired, the adjustable journal pins 19 may be drawn down still further, after which they may be locked in place by lock nuts, as shown. By this construction, any desired natural period of oscillation may be set up within certain limits by making proper adjustments of the adjustable studs 19. The inner casing is preferably rather heavy, so that a fairly low natural period of oscillation may be adjusted for. Also, a heavy casing is adapted to store more kinetic energy if resiliently supported, and for this reason a heavy casing and springs of corresponding strength and stiffness are provided.

The resilient means thus far described consists of initially tensioned spring means, which permits up and down movement of the inner casing with respect to the outer casing. In order to limit the movement of the inner casing in a horizontal plane, suitable leaf springs 25 are securely fastened to re-enforcing bosses 26 projecting inwardly substantially at the midpoint on each side of the outer casing by cap screws 27. These leaf springs 25 are of general Z-shape, and have riveted to opposite sides of the upper end thereof friction pads 28 of suitable friction material, such as leather, re-enforced asbestos and the like, by suitable rivets as shown. The inner pad 28 on each of these Z-shaped springs 25 is seated on a bearing plate 29 held in place by two threaded studs

30. A similar but U-shaped bearing plate 32 is also provided and slidably supported by these studs 30, and is urged against the outer friction pad 28 by springs 34 adjustably held in place by nuts 35. Both of these bearing plates are removable, so that they may be replaced when worn down or when necessary for any other reason. Each of the leaf springs 25 is slotted at an intermediate point to receive the flattened bearing stud 36 riveted into the outer casing O. These studs 36 are mainly provided to re-enforce the leaf springs 25 as far as motion along the plane of these springs is concerned in a horizontal direction, and also to provide a certain amount of friction to absorb the energy of oscillation afforded by such springs.

The bearing plates 29 and 32 and the casing I may move both horizontally and vertically with respect to the friction pads 28, so that a certain amount of braking action in both a horizontal and vertical plane is afforded by each of these friction devices. It should be noted that these devices are located at right angles to each other, and that the friction devices at the ends of the inner casing I take care of up and down as well as sidewise motion of the inner casing; whereas the friction devices on the side of the casing take care of up and down motion as well as endwise movement of the inner casing, so that frictional resistance is afforded in three planes substantially at right angles to each other. Further, the flattened bearing studs 36 afford a certain amount of friction to limit oscillation in two directions at substantially right angles to each other in a horizontal plane.

The inner casing I is provided with a cover 40, having a circumferential groove containing the usual felt gasket 41 to afford a moisture-tight seal between the cover 40 and the casing, this cover being secured in place by cap screws 42 engaging threaded ears extending outwardly from the casing I. A suitable collar is pinned to each of the screws 42 to prevent these screws from falling out of the cover when the cover is removed. The outer casing is provided with a similar cover 43, also provided with a gasket, but this cover is held in place by a quick detachable hasp fastener H. This hasp fastener comprises a hasp member 45 pivotally secured in place between a pair of ears 46 by a cross pin 47. The hasp member 45 is bifurcated and has a curved spring hook 48 pivoted about a pin 49, and has its hooked end engaging a ledge 50 between extensions 51 on the cover 43.

The lower end of the hasp member 45 is provided with a slot which embraces the staple 52 when the hasp member is in the closed position. It should be noted that the pin 47 lies outside of a line connecting the ledge 50 and the pin 49, so that a toggle

action is present tending to hold the hasp member 45 in its closed position. If desired, a padlock may be hung in the staple 52 to provide suitable locking means for the casing.

5 The inner casing is provided with an opening in the side wall containing a flanged insulating bushing 55. The outer casing is provided with a similar opening in which 10 is shown fastened a conduit fitting 56, in which is shown secured a flexible conduit 57. A large number of wires 58 is adapted to be brought into the inner casing I, only two of which have been shown.

15 It will be noted that the openings in the inner and outer casings, respectively, are located a considerable distance apart in adjacent side walls. This is done so that relative movement between the inner and outer casings causes very little angular displacement of these wires, so that they are not apt to be broken due to oscillation of the inner casing due to jars and vibration. The outer casing serves to provide a substantial 20 support for the inner casing, and also provides a suitable housing for the resilient supporting and the frictional energy absorbing mechanism. The outer casing also serves to prevent a sudden change in the temperature 25 of the walls of the inner casing which if permitted would tend to condense moisture in the air in this casing, especially when the change is a lowering of the temperature. This manner of providing a dead 30 air space between the inner and outer casing to a large extent prevents the accumulation 35 of moisture in the inner casing.

40 A supporting and housing structure has thus been provided which includes initially tensioned spring means constructed in a manner so that the initial tension may be varied, if desired, so as to permit any desired natural period of oscillation of the inner casing to be effected within certain 45 limits. Similarly, spring means has been provided to permit oscillation in a horizontal plane, this spring means (springs 25) being of a type which may be initially tensioned toward the center of the casing, if 50 desired. Further, suitable energy absorbing friction devices have been provided which are adapted to absorb energy due to oscillation, regardless of the direction or directions in which the oscillation takes place.

55 Having thus shown and described one specific embodiment of the invention, it is desired to be understood that this has been done for illustrative purposes only and that various changes and modifications may be 60 made to adapt the invention for supporting the various sensitive electro-responsive devices used in practice for the purpose described, without departing from the scope 65 of the invention or the idea of means under- lying the same.

What is desired to be secured by Letters Patent of the United States, is:—

1. In a supporting structure for sensitive electro-responsive devices, the combination with a support, a casing, two sets of springs for resiliently supporting said casing by said support for movement in a horizontal and vertical plane respectively, and a friction device for absorbing energy due to oscillation of said casing in both a vertical and a horizontal plane. 75

2. In a structure for supporting sensitive electro-responsive devices, in combination, an inner casing, an outer casing, opposed initially tensioned springs for supporting 80 said inner casing in said outer casing, and combined spring and friction means mounted in said outer casing, for resiliently supporting said inner casing against endwise displacement and for absorbing energy due to 85 oscillation of said inner casing in both a vertical and horizontal plane.

3. Shock absorbing apparatus for supporting sensitive electro-responsive devices for train control systems on railway vehicles comprising, an outer casing, an inner casing resiliently supported by said outer casing, and unitary means for frictionally limiting the movement of said inner casing in both a horizontal and a vertical plane and for resiliently limiting the movement of said casing 95 in a horizontal plane.

4. Apparatus for supporting sensitive electro-responsive devices for train control systems comprising, an outer casing, an inner casing, means for resiliently supporting said inner casing by said outer casing for both vertical and horizontal oscillatory movement, and friction means acting as a brake to limit the oscillation in both a vertical 100 and a horizontal plane.

5. Apparatus for housing and mounting sensitive electro-responsive devices for train control systems, comprising, an outer casing, an inner casing, means for resiliently and movably supporting the inner casing in the outer casing, an opening in the wall of the outer casing and an opening in the wall of the inner casing for lead in wires, the openings, in the two casings being offset a substantial amount from opposition to each other, whereby lead in wires passing through the two openings will each have a portion disposed substantially parallel to the walls of the casings. 110

6. Apparatus for housing and mounting sensitive electro-responsive devices comprising, an enclosed inner casing carrying such devices, an outer casing, and unitary means wholly within the outer casing and wholly outside the inner casing for resiliently supporting the inner casing, said last mentioned means acting frictionally to subdue oscillation of said inner casing due to jars and vibration. 115 125 130

7. Apparatus for housing and mounting sensitive electro-responsive devices comprising; an outer casing, an inner casing, means movably mounting the inner casing in the outer casing, each casing consisting of a box-like portion; flat springs secured fixedly to one of said casings and extending between friction members spring pressed together and secured to the other casing, said springs and friction members being wholly contained within the outer casing.
8. Apparatus for housing and mounting sensitive electro-responsive devices comprising; an outer casing, an inner casing movably carried in the outer casing, each casing consisting of a box-like body portion, means movably mounting the inner casing in the outer casing, a plurality of springs fixedly secured in vertical planes to one of said casings at points such that one of said springs can move substantially transversely to the movement of another of said springs; a plurality of spring pressed clamping devices secured to the other of said casings at points to clamp said springs; and pads of friction material contained in said clamping devices engaging said springs; whereby movement of said inner casing vertically or horizontally in one vertical plane is frictionally resisted by one of said springs and its associated clamping devices, and movement of said inner casing in another vertical plane transverse to said one vertical plane is frictionally resisted by another of said springs and its associated clamping devices.
9. Apparatus for housing and mounting sensitive electro-responsive devices, comprising, an outer casing, an inner casing therein, means movably mounting the inner casing in the outer casing, friction members fixed to one casing, an arm fixed to the other casing and extending between the friction members, and means pressing the friction members together against the arm.
10. Apparatus for housing and mounting sensitive electro-responsive devices, comprising, an outer casing, an inner casing therein, means movably mounting the inner casing in the outer casing, opposed friction plates carried by one of the casings, a spring arm fixed to the other casing and extending between the friction plates, friction pads fastened to the arm and positioned between the friction plates, and means pressing the plates against the friction pads.

In testimony whereof I hereby affix my signature.

CHARLES S. BUSHNELL.
